UNITED STATES PATENT OFFICE.

BRADLEY DOBIE, OF ELMHURST, NEW YORK, ASSIGNOR TO AMERICAN ARCH COMPANY, A CORPORATION OF DELAWARE.

FURNACE ROOF.

Application filed April 23, 1923. Serial No. 633,906.

To all whom it may concern:

Be it known that I, BRADLEY DOBIE, a citizen of the United States, residing at Elmhurst, in the county of Queens and State of New York, have invented certain new and useful Improvements in Furnace Roofs, of which the following is a specification.

My invention relates to furnace roofs, and is especially concerned with furnaces of circular form or the like, typified by oil still furnaces. Besides simplicity, relatively low cost and facility of construction, the preferred embodiment of the invention here shown affords the advantage of supporting the roof independently of the refractory furnace lining or wall,—with freedom for independent expansion and contraction without lateral stress or strain on such wall,—obviates all risk of collapse of the roof, minimizes spalling and other local deterioration, and allows the roof to be quickly repaired or replaced (in whole or in part) with the least trouble and expense. It also offers the advantage that standard parts (already commercially available) can be employed.

How these and other advantages can be realized through the invention in a novel manner will appear from my description hereinafter of the best construction for the purpose that is known to me.

In the drawings, Fig. 1 is a somewhat diagrammatic illustration of an oil still furnace, in vertical mid-section as indicated by the line 1—1 in Fig. 2, with the intermediate portion broken out and omitted.

Fig. 2 is a plan view of the furnace, with part of the actual roof omitted to make other features of construction clearer.

Fig. 3 is a fragmentary side view with the outer shell of the furnace wall broken open to expose certain features of the roof construction.

Fig. 4 is a fragmentary view somewhat similar to the upper portion of Fig. 1, but showing more details,—certain parts being in section as indicated by the line 4—4 in Fig. 5.

Fig. 5 is a fragmentary plan view of the roof proper and certain associated parts below the line 5—5 in Fig. 4.

In the present instance, there is shown an upright cylindrical still drum 10 supported in the usual manner, and a surrounding cylindrical furnace wall or shell 11. This wall 11 consists of a metallic shell proper 12

with a refractory lining 13, in the form of a wall of the usual construction spaced inward from said shell 12 to afford a thermo-insulative dead air space. As here shown, the still drum 10 extends above the refractory lining 13 (and, indeed, also above the metallic shell 12), and only the space between wall 11 and drum 10 is roofed over.

The refractory roof 15 here illustrated (see, especially, Figs. 1 and 4) has the form of a flat pitched dome with a large opening in its center for the drum 10; in other words, it is virtually a minor zone of a sphere of very large radius. It is also dome-built in that circumferentially adjacent refractory brick composing it divide or abut along substantially or approximately radial planes. As shown in Figs. 2 and 5, indeed, the brick are arranged both convergently and annularly. Instead, however, of being supported by arching interaction with the refractory inner wall or lining 13, this dome 15 is supported quite independently, by suspension from the overlying and circumjacent frame and shell structures 16, 12.

As here shown, the roof 15 is composed of an annular series of radial rows of brick 17 and 18. The rows 17 are of uniform width, being composed of standard "bung" brick (such as are now in use for roofing metallurgical furnaces) with their undercut heads engaged between curved rods 19, 19 themselves secured at opposite ends by clamps 20 in the usual manner. These radial bungs 17 are suspended at their ends by means of hanger rods 21 attached to the clamps 20 and having at their upper ends anchor pieces 22 to take over the vertical flanges of supporting members 23 and 24 consisting of angle bars bent to ring form, one rather close around the drum 10 and the other inside the shell 12. The brick 18 intermediate the bungs 17 rest on the latter, and have shoulders 25 on their ends (Fig. 3) for engaging in corresponding rabbets of the bung brick. These bricks 18 are successively shorter and shorter from the outside inward, so that each row as a whole is of sector-like or triangular shape in plan.

Besides the rings 23 and 24, the supporting structure 16 comprises a polygonal frame consisting of I beams 26, 26 resting on the flanged top of the shell 12 and other I beams 27, 27 extending between them. On the sides of the square thus "circum-

scribed" around the drum 10 rests the inner ring 23, while the outer ring 24 rests on the beams 26 and on short channel beams 28 whose outer ends rest on top of the shell 12 and whose inner ends are secured to the beams 26 and 27.

As shown in Figs. 1, 4 and 5, the innermost of the brick 17 and 18 are of special form, with narrow circumferential ridges 10 29 across their sides for engaging and definitely sealing against the drum 10. At its outer edge, the roof 15 is sealed with the top of the wall in any suitable manner, as by a packing 30 of sand, asbestos wool 15 faced with crushed firebrick and fireclay, or other material. At its periphery, the roof 15 proper is engaged by a row of inclined-faced "abutment" brick 31 resting on sealing material 32 (such as asbestos wool) just 20 outside the topmost shoulder of the wall 13. The brick 31 are surrounded by a flat metal binder ring 33 (here shown as divided into quadrant segments), which serves as a means for holding or crowding the brick 25 17, 18 convergently together toward the drum 10, and for holding the roof 15 in place generally. Inward pressure is exerted on the segments of the ring 33 by appropriately located push rods 34, which are 30 30 yeldingly urged inward by helical compression springs 35 in tubular casings 36 themselves sustained by the circumjacent shell structure 12.

I claim:

35 1. In a furnace of the character described, the combination with an upright drum and a surrounding furnace wall, of a furnace roof around said drum sealed therewith and with said wall, but supported independently of either.

40 2. In a furnace of the character described, the combination with an upright drum and a wall around said drum, of a dome-built 45 suspended refractory brick roof for their interspace, with means for holding the brick of said roof convergently together toward the drum.

3. In a furnace of the character described, the combination with an upright drum and 50 a surrounding refractory wall, of a framework over the interspace between them supported independently of said wall, and a refractory roof for said interspace sealed with drum and wall, and composed of brick 55 suspended from said framework.

4. In a furnace of the character described, the combination with an upright drum and a surrounding wall, of a roof for said furnace sealed with said drum and wall, and comprising an annular series of refractory bungs converging toward said drum and suspended by their inner and outer ends.

5. In a furnace of the character described, 60 the combination with an upright drum, a surrounding refractory wall, and a circum-

70 jacent supporting structure, of a polygonal framework circumscribing said drum carried by said supporting structure, with inner and outer supporting rings adjacent said drum and wall, and a dome-built furnace roof around said drum sealed therewith and with said wall, and comprising an annular series of refractory bungs suspended at their inner and outer ends from said rings.

75 6. In a furnace of the character described, the combination with an upright drum and a refractory wall around said drum, of a suspended refractory roof for the interspace supported independently of the refractory wall but sealed therewith, and holding means circumjacent and peripherally engaging said roof sustained against its horizontal thrust independently of said wall.

80 7. In a furnace of the character described, the combination with an upright drum and a refractory lined metal shell around said drum, of a suspended refractory roof for said furnace around said drum supported from said shell.

85 8. A furnace of the character described comprising a metal shell and a refractory lining therewithin, a supporting structure carried by said shell, a dome-built roof of refractory brick suspended from said structure within said shell and sealed to said refractory lining, and means pushing inward from said shell on the periphery of said roof to hold its brick tightly together.

90 9. A refractory furnace roof comprising an annular series of convergent suspended rows of bricks.

95 10. A refractory furnace roof comprising an annular series of converging suspended bungs, and intermediate sector-like rows of brick resting on said bungs.

105 11. A refractory furnace roof comprising a framework with annular supporting members one within another, and an annular series of radial bungs suspended from said annular members.

110 12. A dome-built refractory furnace roof comprising annularly and convergently arranged brick, a peripherally surrounding sustaining structure, and means acting between said structure and the roof periphery for yeldingly pushing inward on the latter to crowd the brick together.

115 13. A refractory furnace roof comprising an annular series of convergent rows of suspended brick, a peripherally surrounding segmental binder ring, and means for exerting inward pressure on the ring segments to hold the brick together.

120 14. A circular furnace roof comprising in combination, an overhead supporting structure, a plurality of radially disposed rows of bricks carried by said structure, a segmental ring at the periphery of the rows,

and means yieldingly pressing against said ring to hold the bricks in contact with one another during expansion and contraction of the roof.

- 5 15. A circular furnace roof comprising in combination, an overhead supporting structure, a plurality of radially disposed rows of bricks carried by said structure, and means for yieldingly pressing said bricks together to maintain them in contact with one another during expansion and contraction.
- 10

16. In a furnace roof, a plurality of rows of suspended bricks radially arranged, a plurality of rows of intermediate bricks 15 suspended from the former, and means yieldingly pressing the bricks together to maintain them in contact with one another during expansion and contraction, the bricks being formed and arranged to constitute a 20 substantially circular roof.

In testimony whereof, I have hereunto signed my name.

BRADLEY DOBIE.
